UNITED STATES PATENT OFFICE.

ISAAC W. WEPPLO, OF CHICAGO, ILLINOIS.

TUBE-CLOSING MACHINE.

1,422,644.

Specification of Letters Patent. Patented July 11, 1922.

Application filed November 10, 1919. Serial No. 337,007.

To all whom it may concern:

Be it known that I, ISAAC W. WEPPLO, a citizen of the United States, residing at Chicago, in the county of Cook and State of Illinois, have invented new and useful Improvements in Tube-Closing Machines, of which the following is a specification.

This invention has relation to collapsible containers, such as paste, glue or paint tubes, and refers more particularly to devices for closing and sealing the bottom end of such tubes after filling.

Collapsible tubes of the kind specified visually have at one end the discharge orifice, closed by a screw-cap. The opposite, bottom end is left open until the tube has been filled, whereupon the bottom edges are pressed together and folded over twice, thereby sealing the bottom end. As such tubes usually are made of very thin and soft metal it occurs frequently that the said sealed bottom unfolds when excessive pressure is applied to the tube, whereupon its contents are apt to run out and be wasted. For this reason it had become good practice to set a clip over the folded end and to press the said clip well into the soft metal, and in this manner it is found possible to provide a tight seal for the tube.

Having the aforesaid conditions in view, my invention resides in the provision of improved means for sealing such containers. A further object is to provide improved devices for guiding the containers during their passage through the machine. The said objects, and the advantageous features of my invention are hereinafter fully set forth and drawings are hereto appended, in which the various elements and combinations are clearly described.

In the drawings:

Figure 1 is a side elevation of a machine embodying the invention.

Figure 2 is a plan view of certain important elements removed from the machine.

Figure 3 shows the same elements as they would appear when beheld from behind the machine of Figure 1.

Figure 4 illustrates one of the members of Fig. 2, but in a different position.

Figure 5 illustrates adjusting devices, the importance of which will hereinafter appear,

Fig. 6 is an enlarged view of the folding mechanism shown in Fig. 1, 55

Fig. 7 is a sectional elevation taken substantially on a line A—A of Fig. 1, when viewed in the direction of the arrow.

Referring in the first instance to Figure 1, the numeral 1 denotes a frame within which a turntable 2 is mounted to rotate, and the said table is provided with axially directed sockets 2^a evenly distributed along its periphery. The said sockets are shaped to receive and to support perpendicularly the containers to be closed and sealed. In practice an operator is assumed to be stationed in front of the machine and to be occupied placing containers in the said sockets while the turntable is moving in the direction of the arrow. Thus he has first placed the tube 3, next the tube 3^a and last the tube 3^b. The said tube 3 is shown entering a mechanism 4, in which its upper edge becomes flattened and folded over. Thence the tubes advance to the position indicated at 3^c, within a mechanism 5 for pressing a clip on the folded edge, after which operation the finished tube is removed from the machine.

The mechanism 5 comprises two elements 80 mounted on slides 6 and 7, respectively, and the said slides are placed in continued alignment and are operated to oscillate in opposite directions through suitable devices, such as a pair of pivotally fixed rocker arms 8, 9, having a toothed end in mesh with toothed racks 10, 11 of the said slides. The upper ends of said rocker arms have projecting studs engaging a pair of cams 12, 13, of a camshaft 14. 85

It is well to mention at this point that the turntable is given an intermittent movement in order that each container may stop long enough to be operated upon by the mechanisms 4 and 5, whereas the camshaft is caused to rotate continuously so that the elements of the said mechanisms 4 and 5 oscillate continually in synchronism with the said turntable.

The slide 6 is shaped to receive a frame 100 15 (see also Figs. 2, 3 and 4), carrying a pair of pivotally fixed gauges 16 and 17, and the said frame is held in place by suitable devices, such as a set screw 18. The function of the said gauges will now be explained. As above mentioned, the container

is closed and folded while passing through the elements 4, after leaving which it travels toward the mechanism 5. During this travel of the container a clip 20 is deftly dropped on to the folded top edge, without disturbing the position of the container within its socket, and it is all-important that no disturbance occur, as otherwise a collision with the parts of the mechanism 5 will follow, and the container will be ruined. But it is not humanly possible to drop the clip so perfectly into place that the ends of the clip coincide with the ends of a fold; contrariwise, the clip always overhangs more or less, one way or the other, as the container passes into the said mechanism 5.

The gauge 17 is turned on its pivot to open or close by extraneous elements and it is held in any position by the light pressure of suitable friction devices such as a coil spring 22. The gauge 16, on the other hand, is held normally open by yielding elements, such as a coil spring 23, so that the tube is free to pass into the mechanism. The slide 7 carries a frame 25 having a front surface 25^a directly opposite a similar surface 15^a of the frame 15. Above the said surface 25^a is mounted, on a plurality of fixed studs 26, a sliding shoe 27, and the said shoe is constantly urged forward by suitable spring elements 28. The said shoe has a heel 27^a which, when the slides draw together, during the entering movement of the container, reaches the inner arms 16^a, 17^a of the gauges, and draws the said gauges into closed position at the same moment the container comes to rest within the mechanism. As stated above, the clip 20 overhangs the container, and the closing movement of the gauges operates to slide the said clip into central position. While the container now remains at a standstill, the slides 6, 7 continue to draw together until the faces 15^a, 25^a touch the sides of the clip 45 and press the latter tightly around the folded edge of the container. Attention is called to a beveled surface 15^b, above the face 15^a, and this beveled surface rides over the top of the clip for the purpose of press- 50 ing the latter securely in place on the container fold.

The slides 6, 7 now commence to draw apart, but actuated by the spring 28, the shoe 27 still keeps the gauges closed until the limit of movement of the said shoe is reached, and the face 27^a commences to recede from the inner gauge arms 16^a, 17^a. Simultaneously the turntable commences to move, and the container moving with it commences to swing the gauge 17 out of the way. Soon the rear edge of the container passes the said gauge and simultaneously the latter is operated upon by a lever 30 to swing into closed position during the remaining 65 short movement of the slide 6, and for this

purpose the said lever 30 is made with a heel 30^a, which strikes a portion of the machine frame 1. It is noted that the gauge 17 is hung on a pivot 31, and that the said pivot is squared to receive the gauge. At 70 the bottom the stud 31 is made with a short arm 31^a, which is acted upon by the end of the lever 30 to close the gauge.

From the above description it is seen that the gauge 17 remains normally closed. 75 Suppose now that a container is entering the mechanism, as indicated in Fig. 2, with the clip 20 overlapping. It is evident that the said clip will strike the gauge 17 before the container comes to rest, and in thus 80 striking, it will be pushed toward its correct central position on the container. The impact of the collision will also cause the said gauge to open slightly, but this is immaterial as the subsequent positive operation 85 of closing the gauges will complete the adjustment.

Reference is now invited to Figs. 5 and 6, which are enlarged views of the portion of the machine carrying the folding elements 90 4. Fig. 5 is a rear elevation and Fig. 6 a front elevation, both substantially in agreement with Fig. 1. A pair of rocker arms 35, 36 are pivoted at the top of the machine frame, and they carry studs 57, 58, which 95 in turn ride in the grooves of a pair of cams 37, 38. Said arms are, at their lower ends connected to reciprocate a pair of slides 48, 49, which carry devices for folding the tube 3. On the slide 48 is mounted a yielding piece 53, which is normally held projected, as shown in Fig. 1, and above the slide is pivotally hung a lever 52, the forward end of which is bent downward to form a rounded hook. The slide 49 carries a bellcrank 50, 100 the upper arm of which is perforated to receive a stud 59 seated in the machine frame. The rocker arm 35 and the bellcrank 50 are both pivotally connected with the slide 49, in which manner said rocker 110 arm operates on the slide 49 to move the bellcrank. Similarly the rocker arm 36 has direct control over the movement of the slide 48.

The operation of the folding mechanism 115 is as follows. The tube 3 reaches the position indicated in Fig. 1 while the slides are drawing together, and the end of the bellcrank and of the bar 53 first come into contact with the tube, the end of which gradually becomes flattened. Further movement of the parts causes the bar 53 to recede until the end of the lever 52 clears the end of said bar, whereupon the lever tilts, urged by the pressure of a spring within the slide 125 (not shown) and drops into the position indicated in Fig. 6, thereby folding the end of the tube over the end of the bellcrank 50. The parts now commence to draw apart, and as the upper arm of said bellcrank is pivoted 130

on the machine frame it follows that the commencement of the retracting movement first of all causes said bellcrank to drop out of the way. Further movement causes the 5 hook of the lever 52 to ride back on top of the bar 53, and the parts then withdraw entirely from the tube. In order to obtain a double fold this operation is repeated.

After the first folding operation is completed it is necessary to maintain the turntable stationary during the second folding operation, and it is also required to elevate the tube in order to bring it into the proper relation to the folding elements as a preliminary to such second folding operation. 10 Such mechanism is well known in tube closing machines of the type herein considered, and for this reason it is only briefly described. On the end of the cam shaft 14 is rigidly affixed a gear wheel 60 intermeshing with a second gear wheel 61, and the latter is twice the size of the former. Concentrically mounted to rotate with the wheel 61 is an annular cam 62, and this cam is provided with two peripheral surfaces 62^a, 62^b 15 of substantially the same length, but the radius of the former is somewhat longer than that of the latter. A bell crank 63 is at one end provided with a roller 64, which is mounted to ride on the cam 62 and yieldingly maintained in engagement with the cam by a spring 65, which latter extends from a support bracket 66. In the opposite end of the bell crank is a pin 67, which is 20 seated in a slide 68 for the purpose of raising and lowering this slide. On the latter is adjustably fixed a shoe 69 having an inclined projection 69^a.

One revolution of the cam shaft 14 completes a fold, and a revolution of the cam carrying gear 61 completes a double fold. During the first folding operation the slide is held lowered and it is elevated for the second fold. Adjacent to and rigid with 25 the gear 61 is a toothed sector 70 and an annular disc 71, and these parts form, together with a pinion 72 and an integral disc 73, both of the turntable drive shaft 75, a Geneva movement imparting intermittent movement 30 to said turntable, as required for the purpose of the two folding operations.

In each rocker-arm is journaled a stud 39 carrying a laterally projecting rod 39^a. On the opposite side of the machine frame are 35 pivoted a pair of pendent bars 40, 41, in which are journaled a pair of blocks 42, and the latter are perforated to receive the said rods 39^a. The rods are slideable in the said blocks for adjustment, and are then clamped 40 in position by suitable means such as by slotting the blocks and drawing the slotted portion together by clamping screws 43. In the manner described a parallel movement is provided, whereby the pendent bars 40, 41 45 are compelled to follow the movement of the

rocker-arms 35, 36. The said bars terminate in cylindrical shanks 40^a, 41^a, on which are clamped a pair of shoes 44, 45.

The folding elements 4 have a way of jerking the container out of alignment in its 70 socket, and they do not always close the fold tightly enough to permit of placing the clip on the container, as described, and it is for the purpose of correcting these defects that the adjusting devices just described are introduced. The parts are so positioned that the container enters the path of travel of the shoes 44, 45 at the time the latter draw together, and the parts are correctly adjusted to cause the said shoes to turn the 75 container in its socket into correct alignment, and also to press the fold together as required for placing the clip.

In the foregoing description I have outlined the invention as actually applied to a 80 machine of the character specified, but I wish to state that I may make such modifications in the structure as may properly come within the scope of the invention.

I claim:

1. In a collapsible tube closing and clip fastening machine, the combination with a tube carrying turntable, a cam shaft relatively timed and a folding mechanism operated from said cam shaft; of devices operated by the cam shaft and co-operating to align, seat and press a clip over the fold of the tube after the clip has been loosely dropped on the tube. 90

2. In a collapsible tube closing and clip fastening machine, a pair of slides, means for alternately drawing said slides together and apart, a Springfield shoe on one slide, an adjustable member on the other slide, a pair of gauges on said member shaped to be 95 operated upon by said shoe to close around a tube carrying a clip as the slides draw together, said adjustable member having an inclined surface riding over the clip in order to press the latter down on the tube. 100

3. In a collapsible tube closing and clip fastening machine, the combination with tube closing and folding elements, of devices for aligning the tube after folding, devices for aligning the clip on the tube, and elements for pressing the clip around the fold of the tube. 110

4. In a collapsible tube closing and clip fastening machine, the combination with elements for folding the edge of the tube, 115 of devices for aligning the clip on the tube, said devices comprising, a slide, a pair of gauges pivoted on the said slide, a second slide, a yielding member on the latter and positioned to engage and close the said gauges, and elements for actuating the said slides. 120

5. In a collapsible tube closing and clip fastening machine, a cam shaft, folding elements, a clip aligning and fastening mech- 130

anism, and devices actuated by the said cam shaft to operate the said folding elements and the clip aligning and fastening mechanism.

5 6. In a collapsible tube sealing and clip fastening machine, the combination with folding elements and a cam shaft actuating said folding elements, of devices operated by the said cam shaft for aligning a clip 10 which has been loosely placed on the tube.

7. In a collapsible tube sealing and clip fastening machine, the combination with a cam shaft operating folding elements, of devices operated by the said cam shaft for 15 aligning the loosely placed clips on the tubes, and co-operating elements for settling the said clips in position on the tubes and for pressing the clips tightly in place on the tubes.

20 8. In a machine of the type referred to, the combination with means for carrying tubes through the machine and cams rotatable in timed relation to said tube carrier; of tube folding means, tube aligning means, 25 means for aligning, seating and clamping clips on the aligned tubes, and means actuated by said cams and connected to operate said tube folding and aligning means and the said clip aligning seating and clamping 30 means.

9. In a tube closing and clip fastening machine, a horizontal turn table carrying receptacles for the tubes to be closed, a horizontal cam shaft above the said table, power 35 transmission elements for simultaneous timed rotation of the said table and shaft, devices for folding the said tubes, devices for aligning the tubes after folding, elements for seating clips and for pressing them on to the said tubes, and a series of 40 cams on the said shaft for effecting the said folding aligning and seating operations.

10. In a machine of the character described, the combination with mechanism 45 for closing the open end of collapsible tubes by flattening and folding the end, of adjustable means operated by said folding

mechanism for pressing the folds tightly together, said means simultaneously operating to align the tubes for further operations. 50

11. In a machine of the type referred to, a cam shaft, tube closing elements, a pair of arms actuated by the cams of said shaft to reciprocate said tube closing elements, a second pair of arms connected to be reciprocated by the first named arms, and shoes attachable to the second arms and adjustable to complete the fold made by the said closing elements. 60

12. In a device of the character described, the combination with a tube carrying turn table and tube closing mechanism, of a pair of slides placed to reciprocate in the line of travel of the tubes on the table, said 65 slides carrying members for aligning clips placed on the tubes and provided with elements for pressing the clips tightly over the fold of the tubes the moment the clips have been properly aligned. 70

13. In a collapsible tube closing machine, a cam carrying shaft, arms engaging two of the cams and connected to operate tube closing and folding elements, means operable by said arms for aligning the tubes 75 after folding, arms engaging a second pair of the cams and connected to reciprocate a pair of slides, and means on said slides for aligning, depressing and tightening clips on the folded end of the tubes. 80

14. In a device of the character described, a pair of reciprocating slides, elements on one slide for aligning a clip on a tube, a member on the other slide for engaging said elements to align the clip, and co-operating devices on the two slides for depressing and closing the clip on the tube. 85

15. In a device of the character specified, a pair of reciprocating slides, clip depressing and closing members attachable to said 90 slides, and elements carried by said members for aligning the clips prior to the depressing and closing operation.

ISAAC W. WEPPLO.
